UNITED STATES PATENT OFFICE.

EDWIN B. GALBREATH AND CHARLES O. GUERNSEY, OF INDIANAPOLIS, INDIANA.

INTERNAL-COMBUSTION ENGINE.

1,124,721.

Specification of Letters Patent.

Patented Jan. 12, 1915.

Application filed May 20, 1912. Serial No. 698,433.

To all whom it may concern:

Be it known that we, EDWIN B. GALBREATH and CHARLES O. GUERNSEY, citizens of the United States, both residing at 5 Indianapolis, in the county of Marion and State of Indiana, have invented a new and useful Internal-Combustion Engine, of which the following is a specification.

It is the object of our invention to raise 10 the efficiency and improve the construction of two cycle internal combustion engines. We accomplish this object largely by producing a better scavenging, the burnt gases being forced out of ports at one end of the 15 engine cylinder by compressed air introduced through ports at the other end thereof. The compressed air is preferably obtained by crank case compression, and the ports are controlled by a cylindrical sleeve 20 or movable cylinder carried by the piston 25 and fitting in an annular space between the stationary cylinder and a depressed cylinder head. By reason of the sleeve, a quantity of air greater than the piston displacement, or even than the total capacity of the 30 cylinder at atmospheric pressure, is thus rendered available for scavenging. The quantity of air thus available for scavenging is further augmented by making the aforesaid sleeve act as a pump piston within the annular space in which it slides, the compressed air thus obtained being also used in part for nebulizing a charge of fuel 35 into the engine cylinder. The amount of such charge is regulated by controlling the operation of a plunger pump.

In the accompanying drawings, which illustrate our invention, Figure 1 is a vertical longitudinal section through an engine 40 embodying my invention; Fig. 2 is a section on the line 2-2 of Fig. 1; Fig. 3 is a horizontal section through the pump and the distributor; and Fig. 4 is a semi-diagrammatic view showing the connections of 45 the pump and distributor, said two parts being shown in section on the lines 4'-4' and 4"-4" respectively of Fig. 3.

The engine cylinders 10, of which there may be any desired number though a two 50 cylinder engine is illustrated, are mounted on a crank case 11, in which is journaled the usual crank shaft 12. Connecting rods 13

connect the cranks of the shaft 12 to the pins 14 in the pistons 15. Each crank of the shaft 12 is preferably formed between 55 two balance disks 16, and with its balance disks 16 is inclosed in a pneumatically separate closed portion or chamber of the crank case 11. Each of such crank case portions or chambers opens upwardly from the bottom of the corresponding cylinder 10, and is provided with an adjustable inlet valve 17 for admitting air from the atmosphere.

Each piston 15 is provided with a cylindrical sleeve 20 which fits into an annular space 21 between the corresponding cylinder 10 and a depressed cylinder head 22, both of which are preferably water jacketed. The sleeve 20 joins the piston below pin 14 except at the ends of such pin, 70 the top face of the piston slanting down on either side of the pin 14 in smooth curves, as shown in Fig. 2. An annular series of inlet ports 23 is provided in the sleeve 20 at its lower end, or where it joins piston 15, 75 this series being broken at the two ends of the pin 14. When the piston 15 is at the bottom of its movement the ports 23 register with the upper ends of correspondingly arranged ports or passages 24 in the walls 80 of the cylinder 10, the lower ends of such passages 24 opening into the space within the cylinder below the piston. The upper end of the cylinder or sleeve 20 is provided with an annular series of exhaust ports 25, 85 which, when the piston and sleeve are in their lowermost position, register with correspondingly arranged exhaust ports 26 in the cylinder 10. The exhaust ports 26 communicate with the atmosphere either directly or through the usual muffler.

The space 21 between each cylinder 10 and its depressed cylinder head 22 is connected by an inwardly opening valve 30 to the atmosphere and by an outward opening 95 valve 31 to a pipe 32, which leads to a small air reservoir 34. By reason of the valves 30 and 31, the sleeve 20 acts as a pump piston within the space 21 to pump air into the reservoir 34. A pipe 35 leads from this 100 reservoir to a distributor, which comprises a casing 36 and a rotary member 37, the casing being connected to pipes 38 equal in number to the number of engine cylinders

2
and equally distributed around the casing 36. The rotary member 37 of the distributor is driven at the same speed as the engine shaft 12, conveniently by being mounted on such shaft, and is provided with a circumferential groove 39 connected to the pipe 35 and with a segmental groove 40 which communicates with the groove 39 and opens successively to the various pipes 38 as the member 37 is rotated. Each pipe 38, in a multi-cylinder engine, is connected through a check valve 41 to the air passage 42 of a nebulizer 43, suitably mounted in the depressed cylinder head 22 of one of the cylinders, and through a relief valve 44 to the space below the piston in the cylinder and crank case of another of the engine cylinders; in a single cylinder engine, the connections of the pipes 38 to all but one of the cylinders and its crank case are simply omitted. The relief valves 44 are set for a higher pressure than are the valves 41, so that they only operate when the back pressure in the valves 41 exceeds the difference in such setting.

30 The air passage 42 of the nebulizer 43 is annular in form, and its inner end is turned inwardly so that it discharges the air into the cylinder in a converging cone. Axially arranged inside of the air passage 42 is a fuel passage 50, the inner end of which is formed into a conical valve seat to receive the conical valve 51, which is held to its seat by a spring 52. When fuel is forced 35 through the passage 50, the valve 51 is lifted from its seat and the fuel is forced into the cylinder in a diverging cone the shape of which is determined by the valve 51. This diverging cone of fuel crosses the converging cone of air from the passage 42 and is effectively nebulized thereby.

40 Fuel is supplied to the passage 50 of each of the nebulizers by a pipe 53, which opens to plunger pump casing 54 and is connected to a fuel supply pipe 56 by a valve 55 which opens toward the pipe 53. The plunger 57 of each plunger pump is directly connected to one of a plurality of reciprocating bars 58, of equal number with 45 the number of engine cylinders and equally distributed around and movable radially in a casing 59. The bars 58 with their associated plungers 57 are pressed radially inward in the casing 59 by springs 60, and 50 may be moved radially outward against the action of such springs by a cam 61, mounted on a shaft passing centrally through the casing 59. This shaft may be either the engine shaft 12 or some other shaft driven at a speed proportional to that of the shaft 12; 55 as shown it is the shaft 12 itself. The inward movement of the bars 58 is limited by a cam 63 rotatably mounted on the shaft 12 or on a shoulder on the cam 61, cam 63 being provided with spiral cam surfaces 64 co-

operating with shoulders 65 on the several bars 58. The cam 63 is adjustable around shaft 12 by any suitable means, which may be connected to the cam by connecting means 66.

70 When a piston of the engine is in or near its uppermost position, or at or near the end of the cylinder remote from the shaft 12, the compressed explosive mixture between the piston or cylinder head is exploded and the piston is forced downward or toward the shaft 12. As the piston moves downward it compresses the air in that portion of the crank case 11 which is directly beneath, such air being prevented from escaping by 75 the valve 17. As the explosion acts on a piston area having only the inner diameter of the sleeve 20, and the piston compresses the air in the subjacent portion or chamber of the crank case for the full area of the 80 outer diameter of the sleeve 20, the compression effected is greater than the piston displacement, and even, if the thickness of the sleeve is made sufficient, than the capacity of the cylinder at atmospheric pres- 90

95 As a piston nears the lower end of its stroke, the exhaust ports 25 and 26 register to relieve any compression remaining within the cylinder, and immediately thereafter the ports 23 register with the upper ends of the passages 24. The compressed air in the crank case 11 now rushes through the passages 24 and ports 23 into the cylinder, effectually scavenging such cylinder 100 by forcing the burnt gases out through the exhaust ports 25 and 26. Because of the excess of compressed air in the crank case, which excess is further augmented as hereinafter pointed out, some waste of atmospheric air through the exhaust ports is allowed, thus insuring the effectual scavenging of the cylinder. The slow movement of the cylinder of the piston when at the extreme lower end of its movement allows 105 110 ample time for this scavenging.

115 As a piston rises, it closes the ports 23 and 25 and compresses the air in the cylinder, at the same time compressing the air in the space 21 and forcing it through the valve 31 and pipe 32 into tank 34. After the ports have been closed, the cam 61 operates the proper plunger 57 to force fuel through the fuel passage 50 of the corresponding nebulizer, the fuel charge being controlled by the 120 cam 63. At the same time, the rotary member 37 of the distributor admits air from the tank 34, through the pipe 35, the proper pipe 38, and the proper valve 41, into the air passage 42 of the nebulizer. The air and fuel 125 pass from the nebulizer into the cylinder in intersecting cones, as pointed out above, the nebulized fuel mixing effectively with the air already in the cylinder. As the compression within the cylinder rises, the back pres- 130

sure in the pipe 38 becomes sufficient to force open the corresponding valve 44, (if the engine has more than one cylinder,) thus allowing part of the air from such pipe to pass into the crank case section of another engine cylinder, preferably a section in which air is then being compressed. This gives the augmented air excess for scavenging, as already referred to. As the piston 10 moves upward, it also, in addition to compressing the air in the cylinder and in the space 21, draws air into the corresponding crank case section through the valve 17.

When the piston is at or near the top of its stroke, the compressed explosive mixture in the cylinder is exploded in suitable manner, as by a spark plug 70 in the depressed cylinder head 22; and the foregoing cycle is repeated. To vary the fuel charge, the 20 cam 63 is adjusted to vary the length of the stroke of the plunger 57.

In some instances, it is desirable to omit the tank 34, in which case the pipes 32 and 35 are directly connected. The distributor 25 may also be omitted, in which case each valve 31 discharges directly into the pipe 38 leading to the corresponding nebulizer. Whether or not the distributor and the tank 30 are used depends very largely on the number of cylinders of the engine, the two cylinder arrangement shown being merely illustrative of the principle of our invention.

What we claim as new is:

1. A two cycle internal combustion engine, 35 comprising a cylinder having a depressed cylinder head separated from the body of the cylinder by an annular space, a piston movable in said cylinder and provided with a sleeve which slidably fits in said annular space, inlet and exhaust valves connected to said annular space, and a nebulizer discharging into said cylinder and supplied with air from said exhaust valve.

2. A two cycle internal combustion engine, 45 comprising a cylinder having a depressed cylinder head separated from the body of the cylinder by an annular space, a piston movable in said cylinder and provided with a sleeve which slidably fits in said annular space, the explosion chamber of the engine being between said piston and said depressed cylinder head, inlet and exhaust valves connected to said annular space, and a tank connected to the exhaust valve.

55 3. A two cycle internal combustion engine, comprising a cylinder having a depressed cylinder head separated from the body of the cylinder by an annular space, a piston movable in said cylinder and provided with a sleeve which moves with the piston and slidably fits in said annular space, the explosion chamber of the engine being between said piston and said depressed cylinder head, and inlet and exhaust valves connected to 60 that end of said annular space toward which

the sleeve moves when the piston approaches the cylinder head.

4. A two cycle internal combustion engine, comprising a cylinder having a depressed cylinder head separated from the body of the cylinder by an annular space, a piston movable in said cylinder and provided with a sleeve which slidably fits in said annular space, the explosion chamber of the engine being between said piston and said depressed cylinder head, said sleeve being provided at its opposite ends with inlet and exhaust ports which coöperate with inlet and exhaust ports in opposite ends of the cylinder, said inlet and exhaust ports in the cylinder being spaced apart lengthwise of the cylinder a greater distance than the length of the piston stroke, inlet and exhaust valves connected to said annular space, and a tank connected to the exhaust valve.

5. A two cycle internal combustion engine, comprising a cylinder having a depressed cylinder head separated from the body of the cylinder by an annular space, a piston movable in said cylinder and provided with a sleeve which slidably fits in said annular space, the explosion chamber of the engine being between said piston and said depressed cylinder head, said sleeve being provided at its opposite ends with inlet and exhaust ports which coöperate with inlet and exhaust ports in opposite ends of the cylinder, inlet and exhaust valves connected to said annular space, and a tank connected to the exhaust valve.

6. A two cycle internal combustion engine, comprising a cylinder having a depressed cylinder head separated from the body of the cylinder by an annular space, a piston movable in said cylinder and provided with a sleeve which slidably fits in said annular space, said sleeve being provided at its opposite ends with inlet and exhaust ports which coöperate with inlet and exhaust ports in opposite ends of the cylinder, said inlet and exhaust ports in the cylinder being spaced apart lengthwise of the cylinder a greater distance than the length of the piston stroke, inlet and exhaust valves connected to said annular space, and a nebulizer discharging into said cylinder and supplied with air from said exhaust valve.

7. A two cycle internal combustion engine, comprising a cylinder having a depressed cylinder head separated from the body of the cylinder by an annular space, a piston movable in said cylinder and provided with a sleeve which slidably fits in said annular space, said sleeve being provided at its opposite ends with inlet and exhaust ports which coöperate with inlet and exhaust ports in opposite ends of the cylinder, inlet and exhaust valves connected to

said annular space, and a nebulizer discharging into said cylinder and supplied with air from said exhaust valve.

8. A two cycle internal combustion engine, comprising a cylinder having a depressed cylinder head separated from the body of the cylinder by an annular space, a piston movable in said cylinder and provided with a sleeve which slidably fits in said annular space, said sleeve being provided at its opposite ends with inlet and exhaust ports which cooperate with inlet and exhaust ports in opposite ends of the cylinder, said inlet and exhaust ports in the cylinder being spaced apart lengthwise of the cylinder a greater distance than the length of the piston stroke, inlet and exhaust valves connected to said annular space, a nebulizer discharging into said cylinder and supplied with air from said exhaust valve, and a plunger pump operated at a speed proportional to the piston speed and supplying fuel to said nebulizer.

9. A two cycle internal combustion engine, comprising a cylinder having a depressed cylinder head separated from the body of the cylinder by an annular space, a piston movable in said cylinder and provided with a sleeve which slidably fits in said annular space, said sleeve being provided at its opposite ends with inlet and exhaust ports which cooperate with inlet and exhaust ports in opposite ends of the cylinder, inlet and exhaust valves connected to said annular space, a nebulizer discharging into said cylinder and supplied with air from said exhaust valve, and a plunger pump operated at a speed proportional to the piston speed and supplying fuel to said nebulizer.

10. A multi-cylinder two cycle internal combustion engine, comprising a plurality of cylinders each having a depressed cylinder head separated from the cylinder by an annular space, a piston fitting into each cylinder and provided with a sleeve which slidably fits in said annular space to serve as a pump piston therein, inlet and exhaust ports controlled by said sleeve, said inlet and exhaust ports being spaced farther apart lengthwise of the cylinder than the length of the piston stroke, a closed casing in which air is compressed by each piston as it moves away from the corresponding cylinder head, inlet and exhaust valves connected with the annular space surrounding each cylinder head, and means for admitting air compressed by the pump action of the sleeves in said annular spaces into said closed casings when air is being compressed in the latter.

11. A multi-cylinder two cycle internal combustion engine, comprising a plurality of cylinders each having a depressed cylinder head separated from the cylinder by an

annular space, a piston fitting into each cylinder and provided with a sleeve which slidably fits in said annular space to serve as a pump piston therein, inlet and exhaust ports controlled by said sleeve, a closed casing in which air is compressed by each piston as it moves away from the corresponding cylinder head, inlet and exhaust valves connected with the annular space surrounding each cylinder head, and means for admitting air compressed by the pump action of the sleeves in said annular spaces into said closed casings when air is being compressed in the latter.

12. A multi-cylinder two cycle internal combustion engine, comprising a plurality of cylinders each having a depressed cylinder head separated from the cylinder by an annular space, a piston fitting into each cylinder and provided with a sleeve which slidably fits in said annular space to serve as a pump piston therein, inlet and exhaust ports controlled by said sleeve, said inlet and exhaust ports being spaced farther apart lengthwise of the cylinder than the length of the piston stroke, a closed casing in which air is compressed by each piston as it moves away from the corresponding cylinder head, inlet and exhaust valves connected with the annular space surrounding each cylinder head, a storage tank connected with said exhaust valves, a distributor connected with said tank and driven at proportional speed with the engine, and connections between said distributor and the various closed casings.

13. A multi-cylinder two cycle internal combustion engine, comprising a plurality of cylinders each having a depressed cylinder head separated from the cylinder by an annular space, a piston fitting into each cylinder and provided with a sleeve which slidably fits in said annular space to serve as a pump piston therein, inlet and exhaust ports controlled by said sleeve, a closed casing in which air is compressed by each piston as it moves away from the corresponding cylinder head, inlet and exhaust valves connected with the annular space surrounding each cylinder head, a storage tank connected with said exhaust valves, a distributor connected with said tank and driven at proportional speed with the engine, and connections between said distributor and the various closed casings.

14. A multi-cylinder two cycle internal combustion engine, comprising a plurality of cylinders each having a depressed cylinder head separated from the cylinder by an annular space, a piston fitting into each cylinder and provided with a sleeve which slidably fits in said annular space to serve as a pump piston therein, inlet and exhaust ports controlled by said sleeve, said inlet and exhaust ports being spaced farther

- apart lengthwise of the cylinder than the length of the piston stroke, a closed casing in which air is compressed by each piston as it moves away from the corresponding cylinder head, inlet and exhaust valves connected with the annular space surrounding each cylinder head, a storage tank connected with said exhaust valves, a distributor connected with said tank and driven at proportional speed with the engine, connections between said distributor and the various closed casings, nebulizers feeding the various cylinders, and connections from said distributors to the air passages of the nebulizers.
15. A multi-cylinder two cycle internal combustion engine, comprising a plurality of cylinders each having a depressed cylinder head separated from the cylinder by an annular space, a piston fitting into each cylinder and provided with a sleeve which slidably fits in said annular space to serve as a pump piston therein, inlet and exhaust ports controlled by said sleeve, a closed casing in which air is compressed by each piston as it moves away from the corresponding cylinder head, inlet and exhaust valves connected with the annular space surrounding each cylinder head, a storage tank connected with said exhaust valve, a distributor connected with said tank and driven at proportional speed with the engine, connections between said distributor and the various closed casings, nebulizers feeding the various cylinders, and connections from said distributors to the air passages of the nebulizers.
16. A multi-cylinder two cycle internal combustion engine, comprising a plurality of cylinders each having a depressed cylinder head separated from the cylinder by an annular space, a piston fitting into each cylinder and provided with a sleeve which slidably fits in said annular space to serve as a pump piston therein, inlet and exhaust ports controlled by said sleeve, said inlet and exhaust ports being spaced apart lengthwise of the cylinder a greater distance than the length of the piston stroke, inlet and exhaust valves connected with the annular space surrounding each cylinder head, a storage tank connected with said exhaust valves, a distributor connected with said tank and driven at proportional speed with the engine, nebulizers feeding the various cylinders, and connections from said distributors to the air passages of the nebulizers.
17. A multi-cylinder two cycle internal combustion engine, comprising a plurality of cylinders each having a depressed cylinder head separated from the cylinder by an annular space, a piston fitting into each cylinder and provided with a sleeve which slidably fits in said annular space to serve as a
- pump piston therein, inlet and exhaust ports controlled by said sleeve, inlet and exhaust valves connected with the annular space surrounding each cylinder head, a storage tank connected with said exhaust valves, a distributor connected with said tank and driven at proportional speed with the engine, nebulizers feeding the various cylinders, and connections from said distributor to the air passages of the nebulizers.
18. A two cycle internal combustion engine, comprising a cylinder having a depressed cylinder head separated from the body of the cylinder by an annular space, a piston movable in said cylinder and provided with a sleeve which moves with the piston and slidably fits in said annular space and forms a pump piston therein, the explosion chamber of the engine being between said piston and said depressed cylinder head, and valves connected to said space so that the sleeve makes its compression stroke when the piston approaches the cylinder head.
19. An internal combustion engine comprising a cylinder, a piston, a nebulizer discharging into the cylinder, a plunger pump supplying the fuel passage of said nebulizer, means for operating said plunger pump at a speed proportional to the engine speed, means for adjusting the length of stroke of said plunger pump, a source of air supply under pressure, and a distributor driven at a speed proportional to the engine speed and admitting air to the air passage of said nebulizer when fuel is being supplied by said plunger pump to the fuel passage thereof.
20. An internal combustion engine, comprising a plurality of cylinders, a piston reciprocable in each cylinder, a plurality of air compressors the movable elements of which are reciprocable with the various pistons, a reservoir into which said air compressors discharge, fuel nebulizers discharging into the respective cylinders and supplied with compressed air from said reservoir, and a distributor operated at a speed proportional to the engine speed and controlling the supply of air from said reservoir to said nebulizers.
21. An internal combustion engine, comprising a plurality of cylinders, a piston reciprocable in each cylinder, a plurality of air compressors the movable elements of which are reciprocable with the various pistons, fuel nebulizers discharging into the respective cylinders and supplied with compressed air from said air compressors, and a distributor operated at a speed proportional to the engine speed and controlling the supply of air from said air compressors to said nebulizers.
22. A two cycle internal combustion engine, comprising a cylinder having a depressed cylinder head separated from the

3
body of the cylinder by an annular space, a piston movable in said cylinder and provided with a sleeve which slidingly fits in said annular space, inlet and exhaust valves connected to said annular space, a nebulizer discharging into said cylinder and supplied with air from said exhaust valve, and a plunger pump operated at a speed proportional to the piston speed and supplying fuel to said nebulizer.

In witness whereof, we have hereunto set our hands and seals at Indianapolis, Indiana, this 13th day of May, A. D. one thousand nine hundred and twelve.
